UNITED STATES PATENT OFFICE.

NAVIGLIO BASSI GALLEGUILLOS, OF PHILADELPHIA, PENNSYLVANIA.

DRINKING UTENSIL.

1,340,886.

Specification of Letters Patent. Patented May 25, 1920.

Application filed March 22, 1920. Serial No. 367,746.

To all whom it may concern:

Be it known that I, NAVIGLIO BASSI GALLEGUILLOS, a citizen of Chili, residing at Philadelphia, in the county of Philadelphia and State of Pennsylvania, have invented 5 certain new and useful Improvements in Drinking Utensils, of which the following is a specification.

One object of my invention is to provide 10 an improved drinking utensil which will be so constructed that when used for drinking purposes a person in order to drink liquid therefrom will be compelled to suck the liquid through comparatively small 15 ducts or passages so that before swallowing, the liquid will have time to properly mix with the saliva in the mouth rendering the liquid in better condition for digestive or assimilative purposes.

Another object is to so construct my improved drinking utensil that when used as 20 above described a portion of air will be sucked into the mouth with the liquid, and oxygen from the air will combine with the 25 liquid in such manner as to avoid stomach disorders which often occur when a person merely pours liquid into the mouth and swallows large volumes of the liquid in an unadulterated state.

A further object is to so carry out the 30 features of my invention that they may be embodied in an ordinary cup or glass within the thickness of the walls of the same and so that liquid can be conveniently sucked 35 therefrom together with a portion of air as above described.

These objects, and other advantageous 40 ends which will be described hereinafter, I attain in the following manner, reference being had to the accompanying drawings 45 in which—

Figure 1 is a top plan view of a drinking cup made in accordance with my invention,

Fig. 2 is an elevation of said cup shown 45 partly in section; the section being taken on the line 2—2 of Fig. 1,

Fig. 3 is a fragmentary top plan view showing a slightly modified form of my invention embodied in a cup,

Fig. 4 is a fragmentary elevation partly 50 in section; the section being taken on the line 4—4 of Fig. 3,

Fig. 5 is a fragmentary top plan view showing another modified form of my invention embodied within a cup, and

Fig. 6 is a fragmentary sectional elevation taken on the line 6—6 of Fig. 5.

Referring to Figs. 1 and 2, 7 represents a cup or similar utensil which may be made of glass, china, porcelain or any other material from which drinking utensils are usually made and in the present instance the side wall 8 of the cup has a number of outwardly curved portions 9 leading downwardly from the top edge 10 and within the confines of each of these portions 9 are located ducts or passages 11 which are formed by molding or blowing the same within the side wall 8. The tops of the ducts 11 lead to the top edge 10 and the bottoms of the ducts open into the cup adjacent the bottom thereof. Other ducts or passages 12 are formed within the wall 10 between the groups of ducts 11; said ducts 12 curving downwardly and having their ends 13 leading to the top edge 10 adjacent the group of ducts 11 within the confines of the portions 9. These ducts 12 have openings 14 which communicate with the atmosphere at the outside of the cup; said openings being positioned between adjacent portions 9 and a sufficient distance below the top edge 10 so as not to be closed during the use of the utensil. Thus each of the curved portions 9 contains the open top ends of a group of 85 the ducts 11 and ducts 13 as clearly shown in Fig. 1.

In the use of the device above described a person with the mouth embracing one of the curved portions 9 sucks through the 90 ducts 11 and 13 and in so doing liquid from within the cup will pass upwardly through the ducts 11 and air will be drawn into the mouth through the ends 13 of the ducts 12 together with the liquid. The sucking action causes the glands of the mouth to secrete saliva which properly mixes with the liquid and the oxygen from the air will also combine with the liquid before the same is swallowed; thus producing the above 95 mentioned advantageous results.

In the form of my invention shown in Figs. 3 and 4 I have illustrated the wall of the utensil bulged inwardly as shown at 15 and provided with a single duct 11^a which leads downwardly and communicates with the interior of the cup adjacent its bottom in the same manner as the ducts 11 above mentioned. The wall of the cup also includes air ducts 12^a which are also curved 105 110

downwardly and these air ducts have their ends 13^a leading to the top edge 10^a of the cup in the same manner as described in connection with the ends 13 of the ducts 12. 5 Certain of the ends of the ducts 12^a open adjacent the top of the liquid ducts 11^a so that a person using the utensil shown in Figs. 3 and 4 would place the mouth over the top of the portion 15 and the passage 11^a 10 and adjacent ends 13^a of the air ducts 12^a would be within the confines of the mouth so that in sucking up through the duct 11^a air would also be drawn into the mouth through the ends 13^a of the air ducts 12^a.

15 In the form of my invention shown in Figs. 5 and 6 the construction is substantially similar to that described in connection with Figs. 3 and 4 with exception that the air duct 12^b is positioned in front of the liquid duct 11^b and extends downward as 20 shown in Fig. 6 and has an opening 16 to the atmosphere.

While I have described my invention as taking a particular form, it will be understood that the various parts of my invention may be changed without departing from the spirit thereof, and hence I do not limit myself to the precise construction set forth; but consider that I am at liberty to 25

make such changes and alterations as fairly come within the scope of the appended claims.

Having thus described my invention, what I claim as new and desire to secure by Letters Patent is:—

1. A drinking utensil of the character described having an air duct; and a liquid duct leading to the interior of the utensil, said air duct and liquid duct being located comparatively close together to permit air 40 and liquid to be simultaneously sucked therethrough; substantially as described.

2. A drinking utensil having a liquid duct formed in the wall thereof and extending downwardly from its top edge and communicating with the interior of the utensil adjacent its bottom; and an air duct formed in said wall and having an opening adjacent the top opening of said liquid duct, said air duct having another opening to the atmosphere; substantially as described.

In testimony whereof I have signed my name to this specification in the presence of two subscribing witnesses.

NAVIGLIO BASSI GALLEGUILLOS.
